UNITED STATES PATENT OFFICE.

GEORGE H. KAUFMAN, OF MARIENVILLE, PENNSYLVANIA, ASSIGNOR OF
ONE-HALF TO ISAAC A. GRUBBS, OF MARIENVILLE, PENNSYLVANIA.

FENCE-POST.

No. 858,345.

Specification of Letters Patent.

Patented June 25, 1907.

Application filed October 13, 1906. Serial No. 838,795.

To all whom it may concern:

Be it known that I, GEORGE H. KAUFMAN, a citizen of the United States, residing at Marienville, in the county of Forest, State of Pennsylvania, have invented certain new and useful Improvements in Fence-Posts; and I do hereby declare the following to be a full, clear, and exact description of the invention, such as will enable others skilled in the art to which it appertains to make and use the same.

This invention has reference to fenceposts, and especially to devices of that class formed from a blank sheet-metal and provided with wire clamps for the attachment of the line wires.

The particular improvements consist in the formation of a plurality of notches in the web of the post for the reception of the clamps, whereby the position of the several line wires may be adjusted with respect to each other, and in the construction of the clamps from a single strip of spring wire bent to form a horizontal V-shaped member having looped ends extended vertically downward and adapted to bear against the sides of the web of the post when the clamp is in place, the apex of the V-shaped member fitting in the notches above mentioned, and the looped ends thereof extending beyond the outer face of the wing portion of the post to form seats for the line wires.

The invention will be readily understood from the following detailed description, and its preferred embodiment is illustrated in the accompanying drawings in which

Figure 1 is a front elevation of a fence post constructed in accordance with the present invention and provided with the improved clamps. Fig. 2 is a rear elevation. Fig. 3 is a side elevation. Fig. 4 is a transverse horizontal section taken on the line 4—4 of Fig. 1.

Like parts are designated by corresponding reference numerals in the several views.

The fence post generally designated 5, is of approximately T-shape, and is formed from a sheet-metal blank doubled upon itself intermediate of its longitudinal edges to form the web portion 6, the edge portions being bent in opposite directions at right angles to the web, and constituting the wings 7 of the post. The web is provided at its outer edge with a series of notches or recesses 8.

The clamps for the line wires are each formed from a single strip of spring wire bent intermediate its ends to form the approximately V-shaped upper member 9, the ends of which are looped as at 10 and then extended downwardly, as at 11, the extreme ends of such extensions being bent inwardly toward each other as at 12.

When the clamps are in place upon the post, the loop 13 formed at the apex of the V-shaped horizontal member of each clamp fits in one of the notches 8 in the post web, the indent ends 12 of the vertical sides of the clamp bearing against the opposite faces of the web. In such position the looped ends 10 of the upper member of the clamp project sufficiently beyond the side edges of the wing 7 of the post to enable the line wires to be passed therethrough.

Owing to the construction of the clamps from spring wire, their side members 11 will bear against the inner face of the post wings 7, while the indent ends 12 of the sides bear upon the opposite faces of the web 6, thus holding the clamps firmly in place upon the post, the reception of the loop 13 in the seat formed by the notches 8 serving to further prevent any longitudinal movement of the clamps when once positioned.

What is claimed is:

1. In combination with a T-shaped post including a web provided with a series of notches in its outer edge, and a pair of oppositely extending wings disposed at right angles to said web, of a clamp removably secured to said post and comprising a horizontal V-shaped member having looped ends projecting beyond the edges of said wings and adapted to receive the line wires, and vertical side members adapted to bear against the inner face of said wings, the apex of said V-shaped member fitting in one of the notches in said web.

2. In combination with a T-shaped post including a web provided with a series of notches in its outer edge, and a pair of oppositely extending wings disposed at right angles to said web, of a clamp removably secured to said post and formed of a single strip of spring wire, said clamp comprising a horizontal V-shaped member having looped ends projecting beyond the edges of said wings

and adapted to receive the line wires, and vertical side members adapted to bear against the inner face of said wings, said side members having inbent ends adapted to bear against opposite faces of said web, the apex of said V-shaped member fitting in one of the notches in said web.

In testimony whereof, I affix my signature, in presence of two witnesses.

GEORGE H. KAUFMAN.
